UNITED STATES PATENT OFFICE

2,457,623

SHOE TREE

George Albino, Waterbury, Conn.

Application June 17, 1946, Serial No. 677,184

9 Claims. (Cl. 12—128.6)

1

This invention relates to improvements in shoe trees, and more particularly to an adjustable shoe tree adapted to fit a shoe at different periods of its wear.

One object of the present invention is to provide a shoe tree of the above nature, which is especially adapted to be made from molded plastic, and having a manually releasable lock slide for holding the toe part and heel part of the shoe tree in any of its adjusted positions.

A further object is to provide a shoe tree of the above nature in which the toe part and heel part are each made of two hollow sections cemented together at their abutting faces and reinforced by dowel pins.

A further object is to provide a device of the above nature which will be simple in construction, inexpensive to manufacture, easy to install and manipulate, compact, ornamental in appearance, and very efficient and durable in use.

With these and other objects in view, there has been illustrated on the accompanying drawing, one form in which the invention may conveniently be embodied in practice.

In the drawings,

Fig. 1 represents a side view of one half of the shoe tree comprising a fore part and a heel part, the flexible link connecting said parts, and the sliding locking bar, shown in section along the line 1—1 of Fig. 2, and also showing in dotted lines the raised position of the heel part before assembly in the shoe.

Fig. 2 is a plan view of the shoe tree in its operating position.

Fig. 3 is a rear view of the heel part of the shoe tree showing in cross section the connecting link taken through one of the unused notches thereof.

Fig. 4 is a fragmentary sectional view of the same, taken along the line 4—4 of Fig. 3, looking downwardly.

The present invention permits shoes, when not in use to be kept in a stretched condition in their original shape and size, thus prolonging greatly the life thereof.

The shoe tree of the present invention may be collapsed quickly to facilitate removal from the shoe and may be easily extended lengthwise after insertion in the shoe to expand and stretch it to its normal size.

Referring now to the drawings in which like reference numerals denote corresponding parts throughout the several views, the letter T indicates the toe part of the shoe, and the letter H the heel part thereof. The toe part T comprises a pair of complementary hollow half sections 10,

2

11 open at their inside sections, and connected together by dowel pins 12 adapted to fit within a plurality of sockets herein shown at 13, 14, 15 formed within the abutting sides of said half sections 10, 11. The toe part T is provided with a vertical rear face 15a as clearly shown in Fig. 1. The heel part H of the shoe comprises a pair of complementary hollow half sections 16, 17 having a plurality of holes herein shown as 18, 19, 20, 21, for the reception of the dowel pins 12 which serve to hold said half sections 10, 17 together in permanent alignment.

The numeral 22 indicates a top handle for the rear heel part H.

15 Each of the two sets of half sections of the toe part T and heel part H are adapted to be permanently secured together by a layer of cement located between the abutting halves of said parts.

In order to connect flexibly the toe part T to the heel part H, provision is made of a pair of aligned narrow slots 23, 24 in the vertical rear base 15a of said toe part half sections 10, 11 for receiving the forward part of a substantially horizontal link 27 having rounded ends, and which is mounted on a pair of pivot pins 28, 29 secured to enlarged bosses B, B₁ on the interior of the toe part T and heel part H, respectively. The link 27 has an elongated slot 33 near its rear surrounding the pivot pin 29. The rear heel part H is provided with a pair of aligned wide slots 25, 26, preferably dovetailed at their edges for receiving an upwardly inclined lock slide 35 having beveled side edges 36, 37 fitting within said dovetailed slots 25, 26.

25 The front face of the heel part H is inclined as indicated by the numeral 26a.

30 Provision is also made of a plurality of inclined top notches 31, 32, 33, 34 in the top of the horizontal link 27, which notches are adapted to selectively receive the upper edge of a slot 34a formed in the locking slide 35, as clearly shown in Fig. 1.

35 The locking slide 35 is provided with a vertical top handle 38 for convenience in manipulation.

Operation

40 In operation, when it is desired to use the shoe tree, the handle 38 will first be raised to release the link 27. The heel part H will then be adjusted with respect to the toe part T to fit the shoe, not shown. The locking slide 35 will then be depressed until it engages in one of the notches 31, 32, 33, 34 according to the fit of the shoe, whereupon the heel part H will be raised and swung from the full line position as shown in Fig. 1, to the dotted line collapsed position therein. The toe part T will then be inserted into the

shoe, and the heel part H will be swung down to full line position, expanding the shoe to its proper condition for maintaining it stretched when not in use.

While there has been disclosed in this specification one form in which the invention may be embodied, it is to be understood that this form is shown for the purpose of illustration only, and that the invention is not to be limited to the specific disclosures, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a shoe tree, a hollow toe part, a hollow heel part, a link pivotally connected to each of said parts by means of pivot pins embedded in the material of said toe and heel parts, said link having a plurality of notches in its upper surface, and an upstanding locking member slideable in the forward face of said heel part for engaging selectively in any one of said notches according to the fit of the shoe.

2. The invention as defined in claim 1, in which said connecting link is provided with an interior slot embracing the pivot pin of said heel part.

3. The invention as defined in claim 1, in which said toe and heel parts are each constructed of a pair of hollow complementary half sections connected together by cement and reinforced by horizontal dowel pins passing through aligned sockets in said sections.

4. The invention as defined in claim 1, in which said locking slide is provided with an upper manipulating handle, and said heel part is provided with a second manipulating handle.

5. The invention defined in claim 1, in which the rear section of said toe part, and the forward section of said heel part are provided with aligned slots for embracing the connecting link.

6. The invention defined in claim 1, in which the rear face of said toe part is provided with a narrow slot embracing said connecting link, and the forward face of said heel section is provided

with a wide slot for receiving said locking slide, said locking slide having a narrow slot embracing said connecting link.

7. The invention as defined in claim 1, in which 5 said locking slide has beveled side edges, and said heel section is provided with dovetailed slots for receiving said bevelled side edges.

8. In a shoe tree, a hollow toe part, a hollow heel part, said parts each having a narrow slot 10 in their respectively adjacent faces, and being otherwise completely enclosed, a pair of laterally spaced bosses integral with each part at the inner sides of the respective slots, a link disposed in said slots and pivotally connected to each of said parts between the bosses by means of horizontal 15 pivot pins embedded in the material of said bosses, said link having a plurality of notches in its upper surface, and an upstanding locking member slideable in the forward face of said heel part for engaging selectively in any one of said notches according to the fit of the shoe.

9. In a shoe tree, a hollow end part comprising 20 a pair of complementary concave sections disposed in edge-to-edge relation, and constituting 25 a complete enclosure having an end wall traversed by the edges of the sections, a narrow slot in said end wall formed by offset portions of said edges, means securing the remaining portions of said edges together throughout their extent, a pair of 30 spaced interior bosses formed integrally with said section adjacent said slot, a pin secured in said bosses pivotally mounting a link extending through said slot, and a second end part secured to said link.

35 GEORGE ALBINO.
